UNITED STATES PATENT OFFICE.

GREIG ROWAN MATHER, OF LONDON, ENGLAND.

GARMENT-CUTTING DEVICE.

Application filed August 27, 1926, Serial No. 131,999, and in Great Britain June 14, 1926.

This invention relates to devices for the cutting out of garments and of the kind comprising a sheet of material, say paper, on which the shapes or patterns are marked either singly or in multiple, the latter being for the purpose of making the device suitable for different sizes of the same garment.

The device is of the kind in which the sheet is adapted to be laid onto the cloth and to be cut with it, that is to say it is not intended that the shapes shall be cut out of the sheet into loose pieces which are individually laid onto the cloth, but the paper pattern sheet of the present invention is instead placed as a whole and in its uncut condition upon the cloth, the pattern shapes or portions of said pattern sheet being advantageously arranged for the most economical cutting of the cloth, the cloth and the pattern sheet being simultaneously cut as if they were one fabric, with the various pattern portions preferably having been previously pinned or otherwise attached to the cloth so that when the pattern sheet is cut with the cloth each pattern portion or shape will be attached by the pin or equivalent fastening means to the corresponding cut portion of the fabric.

The invention is designed chiefly for the purpose of enabling the one sheet to be used on cloth of different widths, for example it may be used on cloth 36 inches wide or on cloth 54 inches wide.

It will be evident that if a sheet of shapes as hitherto made was suitable for the narrower material it would, if applied to the wider cloth, result in considerable waste of the cloth and conversely if made for wider cloth it could not be advantageously used on narrower material. The present invention enables a person having a sheet of shapes to choose either width of material and use the shapes or patterns economically and satisfactorily for whichever width is chosen.

The invention may be broadly described as consisting in making the sheet of shapes with one (first) part suitable for two widths of cloth and with another (second) part suitable for use with the first part on a narrower width of cloth and another (third) part also suitable for use with the first part and suitable for use with the wider cloth. The said second and third parts will, in a general way, carry much the same shapes.

When the sheet is used either the second part or the third part will not be required.

The most convenient way of making the sheet is to have one main part with the other parts on two adjacent sides of the main part.

In a simple form the sheet will comprise a rectangular part wherein, one side will be extended to form the second part and the other side will be extended to form the third part. The markings of the shapes may overlap from what we have called the second and third parts onto the first part.

An example of the invention is shown in the accompanying drawings in which a sheet of paper or other suitable material carries the patterns or shapes and is divided into three parts, 1, 2 and 3 respectively.

The width of the parts 1 and 2 may be taken along the line $x-y$ as 54 inches and the width of the parts 1 and 3 on the lines $z-y$ as 36 inches.

The part 1 carries multi-outline shapes $a-a$ of substantially known kind and these are used with either the shapes $b-b$ in the part 2 or with the like shapes $c-c$ in the part 3.

If the parts 1 and 2 are used on wide material the part 3 may be thrown away and if parts 1 and 3 are used on narrower material then the part 2 is thrown away. It will be observed that some of the shapes, such as d may extend from the part 2 into part 1 and also from part 3 into part 1.

The shapes or patterns shown are not to be taken as a correctly shaped or as a full set of patterns and it must be understood that any suitable set of shapes may be printed or otherwise marked out in single or multiple manner on the sheet.

For large sheets the part 2 or the part 3 may be provided on a separate sheet with appropriate registering marks on the margins to correctly position the separate sheet beside the larger or main sheet.

Instructions for use may be printed on the sheet in any suitable places.

It will be noted that the pattern sheets of the present invention preferably consist of three pattern portions, a main pattern portion and two auxiliary pattern portions, each of said pattern portions being substantially rectangular, the pattern portions being preferably so dimensioned that one of the dimensions of one of the auxiliary

pattern portions corresponds to the width of one of the materials with which the pattern sheet is adapted to be used while one of the dimensions of the remaining auxiliary pattern portions corresponds to the width of the remaining material with which the pattern sheet of the present invention is adapted to be used. It will also be noted that the patterns or shapes on one of the auxiliary pattern portions are substantially duplicates of the patterns or shapes of the auxiliary pattern portion, so that while materials of two different widths may be conveniently selectively employed with the pattern sheets of the present invention, one and the same garment is in either case cut from the material of selected width. Finally, it will be noted that the auxiliary pattern portions are so arranged with respect to the main pattern portion that the proper dimensions coincide in the formation of what is substantially an L-shaped pattern sheet having a corner portion free from any patterns or shapes completing the pattern sheet in substantially rectangular form.

What I claim is:—

1. A device for cutting out garments comprising a sheet of material marked with patterns for parts of the same garment and divided into three substantially rectangular sections two of which contain patterns that are arranged on adjacent sides of the other part so that either of the said two may be selectively used with the said other part.
2. A device for cutting out cloth for garments consisting of sheet material marked by printing, with a set of patterns for parts of the same garment some in duplicate, said material comprising a main part and two other parts, said three parts being substantially rectangular and said two other parts carrying like patterns either of said two other parts being adapted to be selectively

used with the main part so as to provide with the main part the complete set suitable for use with materials of different widths.

3. A device for cutting out garments consisting of a sheet of material comprising a main pattern portion the two dimensions of which correspond to two different widths of materials from which a garment may be cut, and a plurality of auxiliary pattern portions adapted to be selectively used with the main pattern portion in accordance with the width of the material from which the garment is to be cut.

4. A device for cutting out garments consisting of a sheet of material comprising a main pattern portion the two dimensions of which correspond to two different widths of materials from which a garment may be cut, and a plurality of auxiliary pattern portions adapted to be selectively used with the main pattern portion in accordance with the width of the material from which the garment is to be cut, the patterns of one of said auxiliary pattern portions being substantial duplicates of the patterns of the other of said auxiliary pattern portions.

5. A device for cutting out garments consisting of a sheet of paper comprising a main pattern portion the two dimensions of which correspond to two different widths of materials from which a garment may be cut, and a plurality of auxiliary pattern portions adapted to be selectively used with the main pattern portion in accordance with the width of the material from which the garment is to be cut, said auxiliary pattern portions being arranged on adjacent sides of said main pattern portion with sides of corresponding dimensions of said main and auxiliary pattern portions being coincident.

In testimony whereof I affix my signature.

GREIG R. MATHER.
